UNITED STATES PATENT OFFICE.

EDWARD D. SCHMITT, OF BALTIMORE, MARYLAND, ASSIGNOR TO THE PURE FOOD PROCESS COMPANY, OF BALTIMORE, MARYLAND, A CORPORATION OF MARYLAND.

JAR-CAP.

1,163,039.

Specification of Letters Patent.

Patented Dec. 7, 1915.

Application filed January 14, 1915. Serial No. 2,147.

To all whom it may concern:

Be it known that I, EDWARD D. SCHMITT, a citizen of the United States, residing at Baltimore, State of Maryland, have invented certain new and useful Improvements in Jar-Caps, of which the following is a specification.

This invention relates to improvements in jar caps.

10 The object of the invention is to provide a cap, which although made of comparatively heavy tin, may be readily removed by hand. In my Patent Number 1,075,125, dated October 7, 1913, I have shown and described 15 a cap of hard metal, especially adapted for hermetically sealing jars, in which the contents are subjected to considerable pressure and in that case, a securing rim is provided having an inclined inner wall, to the bottom 20 of which is attached, an opening lever, the inner wall serving as a fulcrum for the opening lever in the opening operation, whereby the metal of the closing rim between the notches, or cut out portions, may be twisted 25 apart. In the present case, I dispense with the inclined inner wall and secure the opening lever to the top of the securing rim, but in order that the metal may be easily broken or twisted apart between the notches, I provide 30 stiffening means on the top of the rim, adjacent to the points where the rupture of the metal takes place. By this construction, I am enabled to provide a cap suitable for milk bottles and the like, where a flat paper 35 or other disk is employed, which cap may be readily removed by hand.

The invention consists in the main, of the provision of a closing member, such as a disk of paper or tin, paper being preferable 40 in instances where the cap is used for milk bottles, in combination with a securing rim provided with a flat upper surface, and a skirt or flange adapted to be bent or crimped into locking engagement with a locking surface on the outside of the jar, adjacent to its mouth, the rim being provided with notches between which the metal is adapted 45 to be twisted, and also with stiffening means for the rim between the notches, there being also a stiffened opening lever attached to the rim adjacent to the notched and stiffened portion of the rim, so that the metal between the notches will be rendered sufficiently stiff 50 to permit a twisting tear of the metal between the notches. A cap of this character

is admirably adapted for milk bottles, since it is securely locked to the bottle, and any effort to remove the cap for the purpose of adulteration of the milk will be readily detected, since it is necessary to tear the rim 60 before the cap can be removed.

In the drawings illustrating the invention, Figure 1 is a perspective view of the cap secured to a milk jar; Fig. 2 is a similar view looking at the cap from another direction. Fig. 3 is a perspective view of the cap with the opening lever raised and in about the position where the rupture of the rim begins. Fig. 4 is a view showing the rim torn through to the last notch on the rim, 70 and Fig. 5 is a sectional view of the cap secured to the bottle. Fig. 6 is a detail sectional view, very much enlarged, of one side of the cap, and lip of the bottle, to show more clearly the engagement between the 75 inner edge of the rim with the closing disk.

It is desirable to use for this closure, a tin of comparatively heavy weight, so that the skirt or flange of the rim may be solidly and firmly locked under the external bead or 80 locking shoulder on the bottle. Tin of the desired weight cannot be torn by a force less than that that could be practically applied in opening the closure. Therefore, I have devised a construction wherein the 85 opening lever will bear such structural relation to the rim as to enable the metal of the rim, between the notches, to be twisted apart. This is accomplished by making the lever and that part of the rim with which the 90 opening lever is integral, stiffer than the rest of the rim, so as to prevent it and the integral part of the rim, from bending in the opening operation.

Referring to the drawings, the numeral 1 95 designates a milk bottle of ordinary construction, provided with an external bead 2 and a seat 3, the seat 3, obviously being for the reception of the ordinary paper disk, commonly used in closing milk bottles. 100

The cap about to be described is one that may be used with the ordinary bottle as shown. The cap consists of a closing disk 4, preferably of paraffin paper, although it should be understood at the outset, that 105 where the cap is used, as it may be, for closing other receptacles than milk bottles, the closing disk 4 may be replaced by a disk of metal or other suitable material.

The numeral 5 designates the securing rim 110

having a flange 6 adapted to be bent or crimped into locking engagement with the under surface of the bead 2, by a suitable capping machine. Integral with the inner edge of the rim 6, which is formed with a flat top or upper surface 7, is an opening lever 8 provided centrally with a stiffening rib 9.

The numeral 10 designates two other stiffening ribs arranged obliquely and extending partly on to the lever and partly across the surface 7 of the rim. Adjacent to these ribs 10 and on the outside of the ribs are two elongated notches 11, with their ends converging toward each other and toward the edge of the flat part 7 of the cap or extending in the direction in which the metal will naturally tear.

In the flange 6, I arrange two other notches 12, extending for almost the entire depth of the flange but leaving some metal between the upper ends of the notches and the outer ends of the notches 10, and also some metal between the lower ends of said notches 12 and the bottom edge of the flange.

It is desirable to make the cap a concrete thing, that is to say, the rim and closing disk are secured together sufficiently to permit handling without separation. To aid in holding the disk in the cap, I turn down the inner edge of the rim to form an annular flange 13 which, in the manufacture of the cap, is embedded into the disk. This flange serves the twofold purpose of assisting in holding the disk in the rim, as well as to prevent lateral movement of the inner circumferential edge of the disk in applying pressure in putting on the seal, that is to say, prevent slipping inward of the disk.

In operation, when it is desired to remove the cap, the opening lever is engaged by the thumb and forefinger and raised, first as shown in Fig. 3 of the drawing. The lever being stiffened, does not bend crosswise, which would defeat the purpose of the structure, but remains straight, as shown in Fig. 4, due to the ribs 9 and 10. This upward movement first brings about a twist at the points *a* twisting the metal at these points, into the notches 11. A further movement of the lever twists the metal apart, at the points *b* bringing about the condition of the cap shown in Fig. 4. A further movement of the lever twists the metal of the flange at the points *c* thus, completely removing a section of the rim. For a temporary closure, it is obvious that the rim and disk may be pressed back on the jar, for keeping fresh, the unused portion of the contents.

While I have shown the cap applied to a jar or receptacle having a large mouth such as milk jars, it will, of course, be understood that it would be equally well adapted as a

closure for bottles or small mouthed receptacles.

Having thus described my invention, what I claim is:

1. A jar cap comprising a closing member, a securing rim formed with a portion adapted to extend over the top of the closing member, and a depending flange adapted to be locked to a locking surface on the exterior of a jar, an opening lever integral with the flat portion of the rim, means for stiffening the opening lever, and also the rim, adjacent to the base of the lever, so that by the lifting of the lever a part of the upper surface of the rim may be twisted off to unlock the seal.

2. A jar cap comprising a closing member, and a rim formed with an upper portion adapted to extend over the closing member, and a depending flange adapted to make locking contact with the locking surface on the exterior of a jar, the rim being provided at one side and in its upper portion, with notches and also having notches in its flange, an opening lever integral with the rim at a point adjacent to the notches, means for stiffening the opening lever and also the rim adjacent to said notches, so that by the raising of the lever, the material between the said notches and the inner edge of the rim, adjacent to the base of the lever, will be twisted apart to tear out a portion of the rim, for unlocking the seal.

3. A jar cap comprising a closing member and a securing rim formed with an upper portion adapted to overlap the closing member, and a flange or skirt adapted to make locking engagement with the locking surface on the exterior of a jar, the rim being provided at one side upon its top and flange with notches, the outer ends of the notches on the rim terminating adjacent to the upper ends of the notches on the flange, an opening lever integral with the rim adjacent to the inner ends of the notches in the upper part of said rim, stiffening ribs adjacent to the notches in the upper portion of the rim, and extending partly on to the stiffening lever and partly on to the rim, whereby the lever and rim are stiffened adjacent to the notches, so that, by the raising of the lever, the material between the inner edge of said rim and the inner ends of the upper notches, and the material between the outer ends of said notches and the upper ends of the notches on the flange, will be twisted out to unlock the seal.

4. A jar cap comprising a closing member, and a securing rim formed with an upper portion adapted to overlap the closing member, and a flange for locking engagement with a locking surface on the exterior of a jar, the securing rim being provided at one side in its upper surface with converging notches, and in its flange with notches whose

- upper ends terminate adjacent to the outer ends of the first mentioned notches, an opening lever integral with the inner edge of the overlapping portion, stiffening ribs between the notches in the upper portion of the rim and extending partly on to the upper portion of the rim and partly on to the opening lever, whereby, by the raising of the lever, the material between the inner edge of said rim and the inner ends of the upper notches, and the material between the outer ends of said notches, and the upper ends of the notches on the flange will be twisted out to unlock the seal.
5. In combination with a jar having a locking shoulder on the exterior surface of the neck thereof, a jar cap having a closing member resting upon the lip of the jar, and a securing rim having a flat upper portion overlapping the closing member and a flange adapted to be forced into locking con-
- tact with the shoulder on the jar, the securing rim being provided in its overlapping portion, and also in its flange, with notches, an opening lever integral with the inner edge of the flat portion of the rim, adjacent to said notches, and stiffening ribs, extending partly on to the opening lever and partly on to the flat portion of the rim adjacent to the upper notches, whereby, by the raising of the lever, the material between the inner edge of the said rim, and the inner ends of the upper notches, and the material between the outer ends of said notches and the upper ends of the notches on the flange, will be twisted out to unlock the seal.
10. 5.. In combination with a jar having a locking shoulder on the exterior surface of the neck thereof, a jar cap having a closing member resting upon the lip of the jar, and a securing rim having a flat upper portion overlapping the closing member and a flange adapted to be forced into locking con-
20. tact with the shoulder on the jar, the securing rim being provided in its overlapping portion, and also in its flange, with notches, an opening lever integral with the inner edge of the flat portion of the rim, adjacent to said notches, and stiffening ribs, extending partly on to the opening lever and partly on to the flat portion of the rim adjacent to the upper notches, whereby, by the raising of the lever, the material between the inner edge of the said rim, and the inner ends of the upper notches, and the material between the outer ends of said notches and the upper ends of the notches on the flange, will be twisted out to unlock the seal.
25. 5.. In combination with a jar having a locking shoulder on the exterior surface of the neck thereof, a jar cap having a closing member resting upon the lip of the jar, and a securing rim having a flat upper portion overlapping the closing member and a flange adapted to be forced into locking con-
30. tact with the shoulder on the jar, the securing rim being provided in its overlapping portion, and also in its flange, with notches, an opening lever integral with the inner edge of the flat portion of the rim, adjacent to said notches, and stiffening ribs, extending partly on to the opening lever and partly on to the flat portion of the rim adjacent to the upper notches, whereby, by the raising of the lever, the material between the inner edge of the said rim, and the inner ends of the upper notches, and the material between the outer ends of said notches and the upper ends of the notches on the flange, will be twisted out to unlock the seal.
35. 5.. In combination with a jar having a locking shoulder on the exterior surface of the neck thereof, a jar cap having a closing member resting upon the lip of the jar, and a securing rim having a flat upper portion overlapping the closing member and a flange adapted to be forced into locking con-
